UNITED STATES PATENT OFFICE.

J. A. BAZIN, OF CANTON, MASSACHUSETTS.

MANUFACTURE OF BRAIDED CORDAGE, WEBBING, &c.

Specification of Letters Patent No. 20,691, dated June 29, 1858.

To all whom it may concern:

Be it known that I, JAMES AMIRaux BAZIN, of Canton, in the county of Norfolk and State of Massachusetts, have invented certain new and useful Improvements in the Manufacture of Cordage, Webbing, &c., and that the following description, taken in connection with the accompanying drawings hereinafter referred to, forms a full and exact specification of the same wherein I have set forth the nature and principles of my said improvements and by which my invention may be distinguished from others of a similar class, together with such parts as I claim and desire to have secured to me by Letters Patent.

In the accompanying plate of drawings Figure 1 represents the manner in which the strands are arranged in manufacturing cordage by my new mode and Fig. 2 the relative position of the strands in webbing or flat bands.

In the usual method of making ropes it is necessary to give the yarns a much harder twist than would be essential for binding the separate fibers together in order to compensate for what is taken out by the counter-twist of the strands, and it is then necessary in laying these strands up into a rope to give them a much harder twist than would otherwise be required. As it is the tendency of each strand to untwist that keeps them all firmly bound together, a hard twisted rope necessarily requiring an equally hard twist in the strands and thereby causing a constant strain upon all the fibers of which it is composed. But where a soft and pliable rope is required, as the twist in the strands must be proportionally reduced, the strands will be liable to be thrown out of place and into kinks by careless usage. To obviate this ropes are sometimes made by braiding which, though it prevents the strands from being thrown out of place, is still more objectionable. As the strands in this case run around spirally in contrary directions a slight twisting of the rope either way will throw all the strain upon one half of their number. And where flat bands are required such as saddle bands, reins &c. the usual method is to make them by weaving like cloth in which case the crossing threads or filling only add weight to the fabric without increasing its strength, while the

this class of goods by braiding as in braiding ropes.

The present invention by which all the hereinbefore mentioned evils are avoided consists in combining the strands of an fibrous material by an interlocking twist in which the strands all take the same spiral form that they would have in a twisted rope of ordinary manufacture, and yet hold each other in place more effectually than can be done by braiding. This new interlocking twist is formed by successively passing every strand either over or under two others so that each of the two so entwined shall in its turn entwine two others.

The manner of forming a rope by my new interlocking twist is clearly shown by colored strands in the drawing in Fig. 1 for instance in which each blue strand passes around one yellow and one red, each red strand around one blue and one yellow and each yellow strand around one red and one blue. Each and every strand interlocking with two others. Fig. 2 shows the same interlocking twist in the manufacture of webbing for flat bands &c. each strand passing around two others viz one red strand passing around two blue ones, and one blue strand around one yellow and one red, the whole forming an interlocking twist in which each and every strand is entwined with two others. In this my new form of twist it will be seen that the strands all take the same spiral form that they would have in twisted rope of ordinary manufacture, and as they hold each other much more rigidly and securely in place and maintain the same spiral form however slight may be the twist in each there can be no unnecessary strain upon the fibers of which they are composed, while under all circumstances, each strand will bear an equal amount of strain with all others and the rope or fabric thus formed will be free from all liability to kink.

In the foregoing description nine is represented as the number of strands to form a rope, but it is obvious that any other number which is the multiple of three may be used six, nine or twelve strands forming a solid rope without any heart-piece, while any greater number increased in the same ratio will form a hollow cylinder which will answer for engine hose stout belting &c., and if any one of the strands is left out a flat band of a single thickness will be formed.

Having thus described my improvements shall state my claim as follows— What I claim as my invention and desire have secured to me by Letters Patent is— My improvement in the manufacture of rdage, webbing or other similar fabrics which consists in laying up or so combining e strands as to form an interlocking twist

in which each and every strand passes around and interlocks with two others as set forth, and thereby brings the strain equally upon each strand.

JAMES A. BAZIN.
